UNITED STATES PATENT OFFICE.

HOWARD A. SMOCK, OF INDIANAPOLIS, INDIANA.

METHOD OF MANUFACTURING STEAM AND HOT-WATER BOILERS.

1,405,346.

Specification of Letters Patent. Patented Jan. 31, 1922.

Application filed July 17, 1920. Serial No. 397,025.

To all whom it may concern:

Be it known that I, HOWARD A. SMOCK, a citizen of the United States, residing at Indianapolis, in the county of Marion and 5 State of Indiana, have invented certain new and useful Improvements in Methods of Manufacturing Steam and Hot-Water Boilers, of which the following is a specification.

This invention relates to a method of constructing and manufacturing steam and hot water boilers; and consists in the provision of a method of boiler construction which is simple, efficient and economical.

The rapid increase in the use, among automobile manufacturers, of an outfit comprising a boiler for simultaneously heating several liquid solutions in different tanks for the removal of grease, dirt, enamel and paint from automobile parts, has created a large 10 demand for a small, compact and portable outfit consisting of a boiler and a number of associated or connected tanks, and it is one of the objects of the present invention to supply such demand.

25 The method of assembling and arranging the various parts of my improved construction, is described in the following specification and illustrated in the accompanying drawings, forming a part hereof, 30 in which—

Figure 1 illustrates the first step in the assembling of my improved boiler. Fig. 2 illustrates the second step in the assembling of the boiler. Fig. 3 is a horizontal sectional view of a complete assembled boiler constructed in accordance with my invention, on the line 3—3 in Fig. 4. Fig. 4 is a central vertical sectional view of an assembled boiler and associated tanks, on the 35 line 4—4 in Fig. 3. Fig. 5 is a fragmentary detail perspective view, on an enlarged scale, showing more clearly the method of joining the ends of the cylinders together. Fig. 6 is a fragmentary cross sectional view, on an 40 enlarged scale, showing a permanent joint for securing the meeting edges of each individual cylinder together.

Referring to the drawings, the complete boiler comprises a plurality of concentrically 45 arranged cylinders 10, 11, 12 and 13. Each of these cylinders is formed out of a flat metal sheet, and when the operation of rolling a sheet is completed the meeting edges of the sheet are held together in a temporary 50 manner by means of a metal cleat 14 which overlaps the meeting edges, the cleat being

secured by a series of rivets 15, as shown most clearly in Figs. 2 and 5. Cleat 14 may be arranged on the outer or the inner surface of the cylinder as conditions may dictate. After the meeting edges of a cylinder, for instance, cylinder 10, which constitutes the inner cylinder of the boiler, are secured by means of a cleat 14 in a temporary way by the rivets 15 the joint is made permanent 60 by welding said cleat fast to the cylinder walls, the heads of rivets 15 being spot welded so that the cylinder becomes an integral structure. A joint as finished in the manner just described is shown by the heavy 65 black portions in Fig. 6. The ends of cylinder 10 are also expanded outwardly, as indicated at 10^a, so as to hold cylinder 11 a uniform distance away to provide an intervening chamber 16, when cylinder 10 is inserted into cylinder 11. Before cylinder 10 is inserted into cylinder 11 the meeting edges of the latter are joined in the same manner as described in connection with cylinder 10, and cylinder 11 is further provided in its 70 wall and near each end with an aperture and into each of said apertures I introduce and fit a tube, 17 and 18 respectively. These tubes are securely welded fast to the cylinder wall, and the tubes provide passageways for 75 the water to pass in and out of chamber 16 when the cylinders are in an assembled condition. After cylinder 10 has been introduced into cylinder 11 the ends of the latter are turned or bent inwardly and are welded 80 fast to the outer surface of the expanded ends 10^a of cylinder 10, whereby an integral 85 structure is formed, and which constitutes the inner section of a completed boiler. This integral structure comprising cylinders 90 10 and 11 is introduced and concentrically arranged in a larger cylinder 12, which forms the inner cylinder of what I designate the outer section of the boiler, so as to bring the free ends of tubes 17 and 18 into the apertures in the wall of cylinder 12. The ends of tubes 17 and 18 are welded fast to the 95 wall of cylinder 12 so that the inner boiler section is retained in a concentric position within cylinder 12. In the operation of 100 bending and forming cylinder 12 its ends are expanded outwardly, as at 12^a, similarly to the expanded end-portions 10^a of cylinder 10, and to the outer periphery of cylinder 12 I attach, by welding, a number of vertically 105 disposed radial blades 20. When cylinder 110 12 is inserted into the large outer cylinder

13, which forms the outer member of the outer boiler section, the blades 20 divide the annular space intervening the outer surface of cylinder 12 and the inner surface of cylinder 13 into a plurality of independent compartments 22 which will be hereinafter more fully described. After cylinder 12 has been inserted into cylinder 13 the outer free ends of blades 20 are welded fast to the inner 10 surface of cylinder 13, and the ends of cylinder 13 are bent inwardly, as at 13^a, similarly to ends 11^a of cylinder 11, and are welded fast to the expanded curved ends 12^a of cylinder 12, whereby an integral 15 boiler, comprising the inner and outer sections, is formed. Instead of constructing and assembling the inner and outer boiler sections in the manner just described, the same may be carried forward by first integrally joining the cylinders 12 and 13 to 20 form the outer section of the boiler and then join thereto the complete inner section at the free ends of tubes 17 and 18.

The completed boiler as just described is 25 arranged upon a base 25 of a boiler setting having also arranged therein the usual grate-bars 26. The boiler is also enclosed by a casing or shell 27 which is provided with a flue-opening 28 through which the 30 burnt products of combustion escape to the chimney.

As shown in Fig. 3 a plurality of tanks, which I designate A, B and C, are arranged around the boiler, and each of these tanks 35 communicates with one of the compartments 22 by means of the conductor pipes 30 and 31, whereby a circulation of the liquid in each tank and its connected compartment 22 is established independently of that in the 40 other tank, when the liquids are heated in the boiler.

In the form and manner in which a boiler is constructed as herein described, it will be observed that the hollow interior A of the 45 inner cylinder 10 serves as a magazine for the holding and the feeding of the coal, or other fuel, into the fire-box B of the boiler, and which constitutes one of the chief features of the present invention.

50 Having thus fully described my invention,

what I desire to secure by Letters Patent, is—

1. The herein described method of manufacturing a steam and hot water boiler which comprises separately constructing of 55 each boiler section in the form of mutually complementary elements, each boiler section being formed of an independent inner and an outer cylinder secured together at their ends and arranged with an intervening 60 water holding chamber between the connected cylinders, and then rigidly connecting the several sections together to form a rigid unitary boiler construction with established communication between the water 65 holding chambers of the different boiler sections.

2. The herein described method of constructing steam and hot water boilers which comprises individually fabricating integral 70 rigid inner and outer section-units in the form of complementary elements, each section being formed of an independent inner and an outer cylinder secured together at their ends spaced apart to form a water 75 holding chamber, between the two cylinders, the chamber in the outer section being divided into independent compartments, and then rigidly connecting said boiler-sections together to form a rigid unitary boiler combination with established communication between one of the compartments and the 80 chamber in the inner boiler section.

3. The method of manufacturing steam and hot water boilers which comprises independently constructing inner and outer 85 boiler sections, each comprising an inner and an outer cylinder spaced apart, with the ends of the cylinders secured together, as mutually complementary stock units, and 90 subsequently assembling these units to form a rigid unitary boiler structure with established communication between the spaces between the walls of each boiler section.

In witness whereof, I have hereunto set 95 my hand and seal at Indianapolis, Indiana, this 8th day of July, A. D. one thousand nine hundred and twenty.

HOWARD A. SMOCK. [L. s.]
